UNITED STATES PATENT OFFICE.

EVERETT B. RICHMOND, OF HARTFORD, CONNECTICUT, ASSIGNOR OF ONE-HALF TO
WINFIELD V. SCHNELL, OF WETHERSFIELD, CONNECTICUT.

WASHTUB.

1,337,272.

Specification of Letters Patent. Patented Apr. 20, 1920.

Application filed March 31, 1919. Serial No. 286,286.

To all whom it may concern:

Be it known that I, EVERETT B. RICHMOND, a citizen of the United States, residing at Hartford, in the county of Hartford, 5 and State of Connecticut, have invented certain new and useful Improvements in Washtubs, of which the following is a specification.

This invention is a wash tub and has for 10 its principal object the production of an efficient means for preventing the splashing or spilling of water from the tub as clothes are being washed therein.

Another object of this invention is the 15 production of a wash tub wherein a guard flange is carried upon the upper edges of the side walls of the tub, this flange extending inwardly and downwardly for a distance into the interior of the tub, thus catching 20 water which splashes upwardly and preventing the same from being thrown or spilled from the tub.

Another object of this invention is the 25 production of a protective flange as specified which has efficient means for connecting the same to a conventional form of tub, this means also reinforcing and strengthening the flange.

A still further object of the invention is 30 the production of a wash tub wherein the guard flange is provided with a depressed portion, whereby an upper edge of a portion of the wall of the tub will be unobstructed to allow a wringer to be secured thereto.

35 One practical form of construction and assembly of the present invention will be hereinafter described and is illustrated in the drawing, in which:—

Figure 1 is a vertical section through the 40 tub constructed in accordance with the present device.

Fig. 2 is a section taken on the line 2—2 of Fig. 1.

Fig. 3 is an enlarged fragmentary vertical 45 sectional view taken on the line 3—3 of Fig. 1.

Fig. 4 is a detail view taken on the line 4—4 of Fig. 2.

In the preferred embodiment of the present 50 invention about to be specifically described it will be seen that the tub is indicated in general at 5 and includes a bottom 6 having side walls 7 and end walls 8 although of course the walls may be continuous 55 the tub being either round, oblong or any

other shape desired since the specific shape or construction of the tub body *per se* does not limit the construction of the invention. As is the usual case, the upper edge of the walls of the tub are rolled over to provide a rim 9 for reinforcing the upper portions of these walls. The guard flange 10 has a sleeve upon its upper edge as shown at 11 this sleeve hooking around under the rim 9 of the walls of the tub, thus connecting the 60 guard flange to the upper portion of the tub. The flange extends downwardly toward the interior of the tub for a slight distance extending at an oblique angle as illustrated clearly in Figs. 1 and 3. The inner edge of 65 the guard flange 10 is rolled to provide a second sleeve 12 having a reinforcing strand 13 extending therethrough thus stiffening the inner edge of the guard flange. Brace brackets 14 have angular ends 15 fixed as 70 indicated at 16 upon the walls of the tub, while these brackets 14 are also provided with angular ends 17 fixed as indicated at 75 18 upon the guard flange 10 adjacent the second sleeve 12 thereof as shown clearly 80 in Fig. 3. Therefore the brace brackets 14 will reinforce the guard flange 10 so that should pressure be applied to the flange adjacent its inner edge, nevertheless it will retain its correct position due to the reinforcement by the brackets 14.

The guard flange 10 has an arcuate depressed portion 19 and along the upper edge of this depressed portion the sleeve 12 is omitted as shown at 20. Thus the depressed 90 portion is fixed by brackets 14 upon one wall of the tub, although the depressed portion is remote from the upper edge of said wall. Accordingly the upper edge of the wall is unobstructed and a conventional 95 form of wringer 21 may be slipped over this unobstructed upper edge. The wall 8 having the depressed portion 19 secured thereto is provided with a reinforcing bracket 22 fixed upon its outer portion, this 100 reinforcing bracket being of substantially U-shaped construction and having oppositely extending feet 23 riveted or otherwise secured at 24 to the outer surface of the wall 8. Accordingly the clamping means 25 of 105 the wringer may be brought into a binding engagement with the bracket 22, it being obvious that a like bracket is provided for each end of the wringer 21. Thus the wringer will be very firmly supported in a 110

vertical position upon the tub adjacent the depressed portion 19 of the guard flange 10.

This flange 10 is also provided with a removable plug 26 adjacent the upper edge thereof whereby when the plug is removed and the tub is tilted, the water will pass from the tub through the opening 26' in the flange 10 which is normally closed by the plug 26.

10 It will be seen that a guard flange is provided for a wash tub which can be attached to conventional forms of tubs and since the flange is provided with bracing brackets 14 it will firmly retain its position as indicated in the drawings. Accordingly when clothes are being washed in the tub and water splashed upwardly beyond the side walls instead of this water splashing from the tub it will be caught under the flange 20 and directed back into the tub again. Further although the flange is provided with a depressed portion to allow the tub to have an unobstructed portion to which a wringer may be connected it will be seen 25 that the guard flange is continuous and is not interrupted and consequently the water cannot splash from the ends of the tub adjacent which the wringer is carried, which it would do if the flange were interrupted to allow of sufficient space for the 30 positioning of a wringer upon the tub. Also as reinforcing brackets are carried on the outer surface of one wall of the tub the wringer may be efficiently connected to the 35 tub to be steadily supported in an operative position. Therefore a very efficient device has been provided which consists of an

attachment for a wash tub in the form of a guard flange which will prevent the accidental splashing of the water from the tub, 40 efficient means being provided for reinforcing the flange, while the flange will allow of a wringer being directly applied to the tub.

The foregoing description and accompanying drawings have reference to what 45 might be considered to be the approved or preferred form of my invention. I desire it to be understood that I may make such changes in the construction, combination and arrangement of parts, materials dimensions, 50 et cetera, as may prove expedient and fall within the scope of the appended claim.

Having thus fully described my invention what I claim as new and desire to secure by Letters Patent, is:—

55 In a device of the class described, the combination of a tub, having walls provided with beads at the upper portion thereof, of a guard flange having a sleeve upon its upper edge hooking about under said beads, 60 said guard flange extending downwardly toward the inner portion of said tub, said guard flange having a second bead upon its lower inner edge, a reinforcing strand carried within the second sleeve, a portion of 65 said flange having a depressed arcuate portion, said bead and said sleeve being cut away above said arcuate portion.

In testimony whereof I affix my signature in presence of two witnesses.

EVERETT B. RICHMOND.
